(57) **CLAIM**

The ornamental design for a controller for railway vehicle, as shown and described.

DESCRIPTION

FIG. 1 is a perspective view of the front, bottom and right side of a controller for railway vehicle showing our new design;
FIG. 2 is a front view thereof;
FIG. 3 is a rear view thereof;
FIG. 4 is a left side view thereof;
FIG. 5 is a right side view thereof;
FIG. 6 is a top plan view thereof; and,
FIG. 7 is a bottom view thereof.
The broken line portion of the figure drawings is included to show unclaimed subject matter only and forms no part of the claimed design.
